UNITED STATES PATENT OFFICE

HENRY C. NATERMAN, OF LOS ANGELES, CALIFORNIA

DESIGN FOR A SHINGLE

Application filed August 24, 1929. Serial No. 32,526. Term of patent 14 years.

To all whom it may concern:

Be it known that I, HENRY C. NATERMAN, a citizen of the United States, residing at Los Angeles, in the county of Los Angeles and State of California, have invented a new, original, and ornamental Design for Shingle, of which the following is a specification, reference being had to the accompanying drawings, forming part thereof.

Fig. 1 is a plan view of a shingle roof for

buildings, illustrating the mass effect of a roof laid with the new design of shingle hereafter claimed.

Fig. 2 is a plan view of a shingle constructed according to my new design.

I claim:

The ornamental design for a shingle, as shown.

In testimony whereof I affix my signature.

HENRY C. NATERMAN.
